William G. Johnston, of Bridgeton N.J.

Letters Patent.

The schedule referred to in these Letters Patent and making part of the same, containing a description in the words of the said William G. Johnston himself of his improvement in a Machine for separating grain from the heads of straw, called, Johnstons Threshing Machine.

Be it known that I, William G. Johnston of Bridgeton, County of Cumberland, and State of New Jersey, have made an improvement in the useful arts, being a Machine for separating grain from the heads of straw, called Johnstons Threshing Machine, which is described as follows. This machine is similar in many respects to other revolving Threshing Machines where the grain is rubbed out from the heads and hulls by means of projecting teeth or points fixed on a cylinder or drum, and a section of a hollow cylinder with teeth called the bed. This arrangement forms no part of my invention.

What I do claim as my peculiar invention and wish to secure by Letters Patent consists in having the bars of iron containing the teeth to turn on centers whenever obstructed by hard substances such as stones &c, getting between the cylinder and concave so that the teeth are preserved from being broken by the turning of these bars. The bars in which the teeth are inserted extend from head to head of the drum or having such shoulders at each end and round openings through which the cutters or screw bolts are inserted which centers first pass through the heads of the cylinder

cylinders; and the bars can be tightened or loosened by nuts put on the inner or outer ends of the screw bolts. These bars are similar to permanent bars till the hard substance enters the machine when they turn as before mentioned. This forms the chief part of my invention. The other smaller improvements I shall not here notice.

For a further illustration of my invention I refer to the model and drawing of the same as deposited in the Patent office.
